UNITED STATES PATENT OFFICE

SANDFORD STODDARD COLE, OF PITTSBURGH, PENNSYLVANIA, ASSIGNOR TO THE
KOPPERS COMPANY, A CORPORATION OF PENNSYLVANIA

STAND-PIPE APPARATUS

Application filed June 8, 1926. Serial No. 114,480.

My invention relates to carbonizing plants, such as by-product coke oven plants, of the Koppers cross-regenerative type, exemplified in the prior Letters Patent of the United States of Joseph Becker for Coking retort oven, No. 1,374,546, granted Apr. 12, 1921. My invention relates more particularly to stand-pipe apparatus for conveying gases of distillation from the individual chambers 10 of such a plant into a collecting main.

One of the objects of the invention is to provide a heat-resistant stand-pipe apparatus, thereby increasing the life of the same.

A second object is to prevent excessive 15 condensation of the gases of distillation while passing through the said apparatus.

A further object of the present invention is to provide a structure the outside of which is relatively cool under working conditions. This is particularly important, due to the somewhat restricted space on top of a coke oven battery which is available for the operators attending to the individual stand-pipes. The discomforts and danger 25 of working around the old type of stand-pipe may be appreciated if it is realized that, under some conditions, said stand-pipes have sometimes been so hot as to be radiant at night.

In addition to the general objects recited above, the invention has, for further objects such other improvements or advantages in construction and operation as may be found to obtain in the structures or devices hereinafter described or claimed.

In order to allow for adjustment due to temperature variations and for constructional purposes, it has been common in the past to provide stand-pipe apparatus which is 40 constituted of two structurally independent, communicating portions, a base portion resting upon the oven structure and an upper portion set into the same which communicates with, and is supported by, the collecting main.

According to my invention, I provide a refractory and insulated base portion for the stand-pipe apparatus which is heat-resisting and structurally strong and able 50 to be used over long periods.

In the accompanying drawings forming a part of this specification and showing, for purposes of exemplification, a preferred form and manner in which the invention may be embodied and practiced but without 55 limiting the claimed invention specifically to such illustrative instance or instances,

Figure 1 is an elevational view, partly in section, of stand-pipe apparatus constructed in accordance with the present invention, and showing, in particular, a novel base portion in such apparatus; and

Figs. 2 and 3 are vertical sectional views of alternative constructions of the said base portion in accordance with the present invention.

Similar characters of reference designate the same parts in each of the several views of the drawings.

In the illustrated embodiment of the invention, and more particularly in Fig. 1 thereof, there is shown a fragmentary portion of a coking chamber 11, provided in the top 12 thereof with a gas-outlet passage 13, through which discharge the gases produced in the distillation of coal within the chamber 11. The chamber 11 may be one of a battery of similar chambers, such, for example, as set forth in the prior patent to Joseph Becker, No. 1,374,546, hereinbefore 75 mentioned. The gases discharging through the outlet 13 pass upwardly through a stand-pipe indicated generally by the character reference S and enter a collecting main C.

The stand-pipe S is preferably constituted of a base portion 14 and an upper portion 15, communicating therewith but structurally independent thereof. The upper portion of the stand-pipe S is rigidly connected to the collecting main C and the weight thereof is carried and suspended by support 90 16 of the collecting main C. By means of this structure, wide variations in the temperature between the oven structure 12 and the collecting main C may be allowed through relative movement of the upper portion 15 and the base portion 14 of the stand-pipe S, as necessary. This relative move- 95 100

ment may amount to as much as several inches.

According to the present invention, the base portion 14 of the stand-pipe S may be variously constructed to provide a combination of refractory, heat-insulating, and structural means, the preferred method of providing for such means being illustrated in Fig. 1. The structural metal shell 17 of sleeve-like configuration rests in, and is supported by, a metal bell 18, which is permanently embedded in the oven structure 12, adapted to receive it. By means of asbestos or other packing material 19, leakage of gas is prevented at the juncture of shell 17 and bell 18. Within the shell 17 are disposed an inner lining 20 and an intermediate lining 21, that are composed of refractory and insulating material, respectively. The refractory material may be of any of the refractories well-known in the art, such as silica or fireclay, and the insulating material may be any suitable asbestos or diatomic and/or cellular composition capable of withstanding and resisting the temperatures involved.

The inner diameter of the lining 20, at its uppermost point, is such as to allow entry of the flanged portion 22 of the pipe 15 and packing material 23 is inserted between the lining 20 and the pipe 15 in order to prevent leakage of gas into the atmosphere. The refractory lining 20 is preferably provided, at its base, with a flanged portion 24 that fits relatively snugly against the bottom of the shell 17 and provides a convenient means of centering the lining 20.

I may take advantage of the well-known low heat conductivity of air by constructing the base portion 14 of the stand-pipe S in a fashion similar to that shown in Fig. 1, but with the omission of the insulating material and the substitution therefor of an air space. This construction is shown particularly in Fig. 2, in which the sleeve 17 and the refractory lining 20 are separated through substantially their entire length by an intervening annular air space 25.

A further alternative mode of accomplishing the objects of the present invention consists in providing a stand-pipe lining that is both refractory and insulatory in nature. In the stand-pipe of Fig. 3, the shell 17 is protected by means of the lining 26, that is composed of material of both a refractory and insulatory nature. Such materials are well known in the arts, but one which I have found particularly suitable is constituted of a refractory material having an extremely high porosity. Such a material may be obtained by mingling with the refractory raw material such as fireclay and/or silica, a desirable quantity of cork or wood particles, or the like, which, in the baking of the refractory, may be ignited and destroyed,

leaving an infinite plurality of cellular spaces in the final refractory material. This high degree of porosity does not injure the refractory quality of the product but causes the same to assume a heat-insulating quality not possessed by the denser refractory product of the same raw material.

The effectiveness of my invention is illustrated by the fact that in stand-pipes as constructed heretofore, the temperature differential between the inside and the outside of the said stand-pipe, where cast-iron pipe is used, may amount to only 200 degrees Fahrenheit, and where a plastic refractory lined pipe is used, to 500 degrees Fahrenheit, whereas, by constructing such stand-pipes in the manner of the present invention, this temperature differential may be increased to as such as 1000 to 1200 degrees Fahrenheit.

The inner surface of the base portion 14, being maintained at a relatively high temperature approximate to that of the gas escaping from the coke oven, is less likely to cause condensation of the tarry content of the gas and thus requires comparatively little attention and cleaning, and eliminates "swabbing" of the stand-pipe, one of the customary operations incident to the operation of a coke oven battery. The temperature of the outer shell 17, which protects the refractory and insulatory lining against breakage from accidental impact, is relatively low and is thus less apt to cause discomfort or injury to the operators, while the life of the stand-pipe, and more particularly the base portion thereof, is greatly lengthened.

My invention is hereinabove set forth and described with reference to a particular embodiment or embodiments, but may variously be embodied with in the scope of the following claims.

I claim as my invention:

1. Apparatus for distilling carbonaceous material and removing gases produced therein comprising in combination, a carbonization chamber, a collecting main, a lower vertical refractory and heat-insulating conduit supported on said carbonization chamber, and an upper conduit adapted to be communicably inserted within the said lower conduit and communicating with, and supported by, said collecting main, and sealing means for preventing the escape of gases into the atmosphere.

2. Apparatus for distilling carbonaceous material and removing gas produced therein, comprising in combination a carbonization chamber, a collecting main, a lower conduit having a lining composed of an inner portion of firebrick and an outer portion of asbestos composition, the said conduit being supported on the said carbonization chamber, and an upper conduit adapted to

be communicably inserted within the said lower conduit and communicating with, and supported by, the said collecting main, and sealing means for preventing the escape of 5 gases into the atmosphere.

3. Apparatus consisting of a pipe element adapted to connect a carbonization chamber to a collecting main for condensed vapors, which element comprises a metal sleeve, a 10 highly cellular heat-insulating material adjacent the inner surface of the said sleeve, and a layer of refractory material on the said layer of heat-insulating material.

4. Apparatus consisting of a pipe element 15 adapted to connect a carbonization chamber to a collecting main for condensed vapors, which element comprises a metal sleeve, a layer of asbestos composition adjacent the inner surface of the said sleeve, and a layer 20 of firebrick on the said layer of asbestos composition.

In testimony whereof, I have hereunto subscribed my name this seventh day of June, 1926.
